UNITED STATES PATENT OFFICE.

WILLIAM R. WHITE, OF NEOGA, ILLINOIS.

GATE.

SPECIFICATION forming part of Letters Patent No. 378,275, dated February 21, 1882.

Application filed August 2, 1886. Serial No. 203,791. (No model.)

To all whom it may concern:

Be it known that I, WILLIAM R. WHITE, of Neoga, in the county of Cumberland and State of Illinois, have made certain new and useful 5 Improvements in Gates, of which the following is a specification.

My invention relates, in general, to improvements in sliding gates of that particular class wherein a gate is operated and controlled by 10 levers; and the novelty consists in the construction, arrangement, and combination of the several parts for service, substantially as hereinafter specifically set forth.

In the accompanying drawings, wherein 15 similar letters of reference denote similar parts, Figure 1 represents a plan view of a gate and section of a fence constructed in accordance with my invention. Fig. 2 is a side elevation thereof, in which the gate is shown 20 by full lines in closed position and by dotted lines in open position. Fig. 3 represents a sectional view taken on the line xx of Fig. 2, showing the means whereby the gate is operated.

25 In the present embodiment of my invention A and B designate the front and rear posts of the gateway, which are respectively placed at the opposite sides of a roadway or other point desired to be closed by the gate.

30 C designates a post, which is placed in alignment with said posts A and B in rear of the latter, and serves the double functions of a support for one end of the rails d of the fence D and a support to which one of the rollers 35 that support the gate is pivoted.

E designates the gate, which consists in the usual longitudinal rails, e, transverse rails e', and braces e''. I preferably make the two upper of the rails e somewhat thicker than the 40 remaining rails comprised in the gate, place them at a distance from each other corresponding to the diameter of the rollers upon which the gate moves, and provide them upon their adjacent edges with projecting ledges e³ 45 e⁴, that are placed, in practice, in peripheral grooves f, formed in the gate-supporting rollers F F', which are pivoted to the posts B and C, respectively. The ledges e³ e⁴ are placed on the sides of the longitudinal rails opposite 50 the uprights or transverse rails e', so that the gate may freely travel past the rollers without

the uprights interfering therewith or having to be cut away specially to allow such movement. The ledges are formed by ordinary lumber (boards) secured to the longitudinal 55 rails opposite the rollers and give additional strength to the rails which bear the weight of the gate, besides serving as the rails for the rollers to travel upon.

I preferably bevel the side walls of the 60 grooves f of the rollers F F' in order to lessen, as far as is practicable, the contact between said sides and the ledges e³ e⁴.

By reference to the drawings it will be observed that the rails d of the fence D terminate 65 at the post C and that the rear end of the gate E extends beyond its post B to the post C when said gate is in closed position. I deem this construction of importance, as I am enabled thereby to dispense with the entire fence-panel, 70 which otherwise would extend between said posts B and C, and to cause the gate itself to close said opening.

I hold the gate in its normal vertical position by a hook, b, which extends from the post 75 B at the lower end thereof and engages the outer surface of the lower rail, e, as shown. I also provide that one or more of said rails e shall project somewhat at the forward end of the gate to engage recesses a, formed in the 80 post A, whereby the gate is held against swinging or turning when closed.

I operate the gate back and forth upon its 85 rollers in and by the following manner and means, to wit:

G designates a swinging rod or bar, one end of which (the lower) is pivoted to the gate, near the bottom thereof, at a point in advance of the post B when said gate is in closed position, while the opposite end of said rod or 90 bar G is pivoted to the forward end of a lever, H, which projects forward from and is pivoted to the post C near the upper end thereof.

I I' designate laterally-projecting levers, 95 which are fulcrumed in the top of supports K K', which are placed at opposite sides and slightly in rear of the post B. The inner ends of the levers I I' are connected by links k k' with the lever H, while their opposite outer ends are provided with pendent pulls k² k³, whereby 100 to operate said levers.

The operation of my improved gate is as fol-

lows: Said gate being closed, a downward pressure upon the outer ends of either of the levers I I' will operate to raise the lever H, and thereby, through the bar or rod G, draw 5 the gate backward or open. When open, the above operation is repeated, and the gate will close.

If desired, the post B may be provided at its top with a transversely-extending timber, 10 to the outer ends of which, at each side of said post, the levers I I' may be fulcrumed; also, that the lever H may be pivoted at its end to the post B, or to a bracket secured thereto and extending therefrom.

15 I am aware that it is old in that class of gates which are opened by a downward pull upon the ends of oppositely-extending opening-levers and closed by an upward push upon the same to connect such levers to a lever pivoted to the fence, which lever is connected with a link pivoted to the front edge of the gate; but such construction is open to the objection that a weak person often cannot close 20 the gate after opening it, owing to the muscular exertion required for the upward push.

I am also aware that it is old in gates both 25 opened and closed by downward movement of the ends of the oppositely-extending operating arms or levers to connect such arms or levers 30 with a link attached to the gate by means of a vertically-reciprocating rod guided by and traveling in eyes on a post to which the said operating-levers are pivoted, such a construction being illustrated in my Patent No. 258,517, 35 granted May 23, 1882; but it is often found difficult with such a construction to get the requisite amount of motion to open and close a long gate, while the vertical rod frequently binds 40 in the guiding-eyes by reason of its becoming bent or the post warping, so as to throw the

eyes out of line. These difficulties, as well as those hereinbefore pointed out, I entirely overcome by my present invention, wherein the vertical sliding rod and the guiding-eyes therefor are dispensed with, and in place 45 thereof is interposed the lever H between the operating-levers I I' and the link G, which is connected to the gate to move past post B as it opens and closes, the levers I I' being connected to lever H near its fulcrum, thereby 50 permitting the gate to be moved in both directions by a short downward movement of the outer ends of the operating arms or levers.

Without limiting myself to the precise construction and arrangement of parts shown, I 55 claim—

The combination, with the sliding gate, the posts B and C, and the rollers carried by said posts, upon which the gate is supported, of the swinging rod or link G, pivoted to the gate, 60 near the bottom thereof, at a point in front of post B, when the gate is closed, and arranged to have its lower end move past said post as the gate opens and closes, a horizontal lever, H, pivoted at one end to post C and pivotally 65 connected at the other end with rod G, and the gate-opening levers I I', pivoted upon opposite sides of the gate and flexibly connected with lever H near its fulcrum, said parts being arranged substantially as described, where- 70 by the gate may be both opened and closed by a short downward pull upon the outer end of either of the opening-levers.

In testimony whereof I have signed my name to this specification in the presence of two sub- 75 scribing witnesses.

WM. R. WHITE.
